CORING APPARATUS

Gordon H. Fisher, Dewey, Okla., assignor to
Phillips Petroleum Company, a corporation of
Delaware

Application April 1, 1941, Serial No. 386,325

9 Claims. (Cl. 255—72)

This invention relates to coring and more particularly to apparatus for obtaining representative cores from subsurface formations.

It is common practice in the petroleum industry to obtain cores from hydrocarbon-bearing formations for the purpose of determining certain reservoir characteristics which are useful in predicting reservoir fluid performance. Virgin reservoirs may be cored usually with a relatively high percentage of core recovery. Depleted formations at shallow depths may be cored with equal success. On the other hand, the coring of depleted reservoirs at greater depths yields a relatively low percentage of core recovery. In the present practice of coring, a drilling fluid is circulated downwardly through the drill pipe and thence upwardly through the annular space between the bore hole and the drill pipe to the surface of the ground where entrained formation cuttings are removed from the drilling fluid. As greater depths of formation are drilled or cored, the pressure of the drilling fluid column increases proportionately. In coring depleted hydrocarbon reservoirs, the pressure of the column of drilling fluid may become so great that the fluid and entrained formation cuttings will flow into the porous formation where the solid materials and the fluid will plug off the pore spaces of the formation instead of circulating to the surface of the ground. If an unconsolidated formation is cored, drilling fluid under considerable pressure will wash away appreciable portions of the core so that which remains is non-representative of the formation cored. If a consolidated formation is cored, the drilling fluid may penetrate the core, contaminating the same. Non-representative or contaminated cores have little or no value for analytical interpretation.

By the practice of my invention, I am able to obtain representative formation cores, which are not contaminated by drilling fluid. The invention will be especially useful in coring low pressure and non-consolidated formations, as none of the high pressure drilling fluid which is used in conjunction with my apparatus comes in contact with the core or formation. Thus, contamination of the core or of the formation from which the core was cut, or other damage to the core which may also be caused by high pressure drilling fluid, is eliminated.

My invention has for its primary object the provision of apparatus for obtaining representative cores from subsurface formations.

Another object of my invention is the provision of apparatus for obtaining representative cores

of low pressure and non-consolidated formations.

A further object of my invention is the provision of apparatus for obtaining subsurface formation cores which are not contaminated with drilling fluid.

Still another object of my invention is the provision of apparatus for obtaining subsurface formation cores by a reciprocating means.

These and additional objects and advantages will be apparent to persons skilled in the art by reference to the following description and annexed drawing, wherein

Figure 1 is an elevation view of one embodiment of my invention, partly in cross section; and

Figure 2 is an elevation view of another embodiment, partly in cross section.

Referring to Figure 1 of the drawing, I have denoted therein a bore hole 10 within which is 20 a string of tubing 11 extending downwardly from the surface of the ground (not shown). Connected to the lower extremity of the string of tubing is a housing, generally indicated by reference numeral 12 and consisting of a casting 13, a removable plug 14, and a member 15 that is threaded into the lower end of the casting. The interior of the housing is bored on several diameters along a central longitudinal axis to form an upper piston passage 16, a lower piston 25 passage 17, a drive head passage 18, and a drive stem passage 19. The casting is also provided with a fluid inlet duct 20, a fluid exhaust duct 21 and a fluid by-pass 22. From an examination of the drawing, it will be noted that fluid inlet duct 20 places the tubing string in communication with the juncture of lower piston passage 17 and drive head passage 18; fluid exhaust duct 21 places upper piston passage 16 in communication with an exhaust conduit 23 that extends 30 upwardly within the tubing string to the surface of the ground; and fluid by-pass 22 establishes communication between piston passage 17 and the upper portion of piston passage 16.

A fluid actuated hammer or piston is contained 45 within the housing and consists of a larger diameter portion 24 and a smaller diameter portion 25 that are arranged to reciprocate in and form effective fluid seals with upper piston passage 16 and lower piston passage 17, respectively. A drive head 26 is movable in passage 18 and forms an effective fluid seal therewith. The extreme upper end surface of the drive head is preferably somewhat smaller in area than the area of the lower end face of the piston. A stem 27 is slidable within 50 passage 19 and is fixedly connected to drive

head 26 and a core barrel 28 that is provided with a plurality of cutting teeth 29 and a core catcher or retainer 30. While a core receptacle of the character illustrated is recommended in the practice of my invention, it will be obvious that various other known types of core receiving devices may be employed with equally satisfactory results.

For the purpose of outlining the mode of operation of the embodiment of the invention depicted in Figure 1, let us assume that the illustrated equipment is assembled and lowered into bore hole 10 so that core barrel 28 rests in the bottom thereof and drive head 26 is in the position shown. Due to the action of gravity, the hammer or piston will rest on drive head 26. A high pressure fluid, such as compressed hydrocarbon gas, is now introduced into tubing string 11 from the surface of the ground from whence it passes through fluid inlet duct 20 and acts against the lower end surface of the hammer to thereby move the hammer upwardly within the housing. When the hammer has moved a predetermined distance upwardly, portion 24 thereof will cover the lower end of exhaust duct 21. Continued upward movement of the hammer will uncover the lower end of by-pass 22, permitting fluid in passage 17 to flow through by-pass 22 and enter the upper part of passage 16, substantially equalizing the unit pressure at both ends of the hammer. Since the upper end surface area of the hammer is larger than its low end surface, it will be apparent that the total loading on the top of the hammer will be correspondingly greater than at the bottom. The differential in total pressure and the force of gravity will therefore urge the hammer downwardly, causing it to strike drive head 26 and thereby force the core barrel downwardly into the formation. During its downward stroke, the hammer first covers the lower end of by-pass duct 22 and then uncovers the lower end of the exhaust duct, permitting the fluid in passage 16 to be exhausted therefrom through exhaust duct 21 and exhaust conduit 23. By the time the hammer completes its downward stroke, the total fluid pressure load on the upper end surface thereof will be materially less than on its lower end surface. The fluid in inlet duct 20 then acts on the lower end of the hammer to again raise it upwardly and the above outlined cycle is repeated. It will be evident that each impact of the hammer against the drive head is directly dependent upon the unit pressure of the actuating fluid and the difference in area of the extreme end surfaces of the hammer. It is therefore a mere matter of design to obtain the desired impact on each stroke of the hammer. In order to prevent injury to the equipment, the tubing string is advanced or "fed" downwardly into the bore hole as the core barrel is driven into the formation. When the core barrel has penetrated the formation to a requisite distance, the supply of fluid to the housing is cut off and the entire assembly is withdrawn from the bore hole.

It is to be borne in mind that, if desired, inner conduit 23 may be connected to the upper end of inlet duct 20, thereby placing exhaust duct 21 in direct communication with tubing string 11. With this arrangement, high pressure fluid is transmitted into the housing through conduit 23 and inlet duct 20, while fluid, so introduced into the housing, is exhausted therefrom through exhaust duct 21 and tubing string 11.

A second embodiment of my invention is shown in Figure 2 wherein like parts of this and the first embodiment are denoted by the same reference numerals. This embodiment is adapted to be employed in obtaining cores through bore holes that are provided with casing 31 which forms an annular space 32 with tubing string 11 and housing 12a. Fluid exhaust duct 21a communicates with annular space 32 in this instance instead of through the exhaust conduit 23 of Figure 1. A suitable packer 33 is positioned in the annular space between the casing and the housing at a depth below the juncture of the exhaust port and the annular space. Except for the above enumerated differences in construction, the apparatus of the second embodiment of the invention is identical with that of the first described embodiment.

The operation of the second embodiment of my invention is likewise the same as that of the first embodiment except that the fluid is exhausted upwardly through annular space 32 instead of through conduit 23.

It is to be understood that the forms of my invention, herewith shown and described, are to be taken as preferred examples of the same, and that various changes in shape, size and arrangement of parts may be resorted to without departing from the spirit of my invention, or the scope of the subjoined claims.

I claim:

1. In apparatus of the character described, the combination comprising a core receiving receptacle adapted to be lowered into a bore hole, a housing, a drive head reciprocably disposed within the housing and connected to the core receptacle, a fluid actuated hammer within the housing for imparting a thrust to the drive head to urge the core receptacle into the formation at the bottom of the bore hole, a conduit in the bore hole for transmitting an actuating fluid at superatmospheric pressure into the housing, and means for exhausting actuating fluid from the housing.

2. In apparatus of the character described, the combination comprising a core receiving receptacle adapted to be lowered to the bottom of a well bore, a housing extending above the receptacle and substantially fixedly positioned in the well bore, a member reciprocable in the housing and secured to the receptacle, and fluid actuated means within the housing and reciprocable independently of the member for imparting a thrust to the member to urge the core receptacle downwardly into the formation at the bottom of the well bore without downward movement of the housing.

3. In apparatus of the character described, the combination comprising a housing adapted to be lowered into a well bore, a core receiving receptacle below the housing and movable with respect thereto, a member slideable in the housing and secured to the receptacle, and a fluid actuated hammer within the housing for imparting a downward thrust to the member to urge the core receptacle downwardly into the formation at the bottom of the well bore without downward movement of the housing.

4. In apparatus of the character described, the combination comprising a pressure fluid conduit adapted to be substantially fixedly disposed in a well bore, a housing secured to the lower end of the conduit, a core receiving receptacle extending below the housing, a member reciprocable in the housing and secured to the receptacle, and

a hammer reciprocable independently of the member within the housing and actuated by pressure fluid transmitted thereto by the conduit for imparting a thrust to the member to urge the core receptacle downwardly into the formation at the bottom of the well bore without downward movement of the housing.

5. In apparatus of the character described, the combination comprising a pressure fluid conduit adapted to be substantially fixedly disposed in a well bore, a housing secured to the lower end of the conduit, a core receiving receptacle exterior the housing and disposed therebelow, a member reciprocable in the housing, means for connecting the member to the receptacle, and a hammer independently reciprocable with respect to the member within the housing and actuated by fluid pressure transmitted thereto by the conduit for imparting an impact thrust to the member to drive the core receptacle downwardly into the formation at the bottom of the well bore without downward movement of the housing.

6. In apparatus of the character described, the combination comprising a core receiving receptacle adapted to be lowered into a bore hole, a housing, a drive head reciprocably disposed within the housing and connected to the core receptacle, a fluid actuated hammer within the housing for imparting a thrust to the drive head to urge the core receptacle into the formation at the bottom of the bore hole, a conduit in the bore hole for transmitting an actuating fluid at superatmospheric pressure into the housing, and a conduit within the first conduit for exhausting actuating fluid from the housing.

7. In apparatus of the character described, the combination comprising a core receiving receptacle adapted to be lowered into a bore hole, a housing, a drive head reciprocably disposed within the housing and connected to the core receptacle, a fluid actuated hammer within the housing for imparting a thrust to the drive head

to urge the core receptacle into the formation at the bottom of the bore hole, a conduit in the bore hole for transmitting an actuating fluid at superatmospheric pressure into the housing, and a conduit exterior the first conduit for exhausting actuating fluid from the housing.

8. In apparatus of the character described, the combination comprising a conduit in a bore hole, a core receiving receptacle adapted to be lowered through the conduit to the bottom of the bore hole, a housing, fluid actuated means within the housing for driving the core receptacle into the formation at the bottom of the bore hole, a conduit for transmitting actuating fluid at superatmospheric pressure into the housing, said last mentioned conduit being disposed within the first mentioned conduit and forming an annular space therewith, fluid exhaust means establishing communication between the interior of the housing and the annular space, and packer means in the annular space below the juncture of the fluid exhaust means and the annular space.

9. In apparatus of the character described, the combination comprising a conduit in a bore hole, a core receiving receptacle adapted to be lowered through the conduit to the bottom of the bore hole, a housing, a drive head reciprocably disposed within the housing and connected to the core receptacle, a fluid actuated hammer within the housing for imparting a thrust to the drive head to urge the core receptacle into the formation at the bottom of the bore hole, a conduit for transmitting actuating fluid at superatmospheric pressure into the housing, said last mentioned conduit being disposed within the first mentioned conduit and forming an annular space therewith, fluid exhaust means establishing communication between the interior of the housing and the annular space, and a packer in the annular space below the juncture of the fluid exhaust means and the annular space.
